No. 711,531.

Patented Oct. 21, 1902.

B. G. REEVES.

PLOW.

(Application filed Aug. 15, 1902.)

(No Model.)

UNITED STATES PATENT OFFICE.

BEVERLY GRAY REEVES, OF DURANGO, TEXAS.

PLOW.

SPECIFICATION forming part of Letters Patent No. 711,531, dated October 21, 1902.

Application filed August 15, 1902. Serial No. 119,722. (No model.)

To all whom it may concern:

Be it known that I, BEVERLY GRAY REEVES, a citizen of the United States, residing at Durango, in the county of Falls and State of Texas, have invented a new and useful Plow, 5 of which the following is a specification.

This invention relates to that class of plows in which a stock or standard is pivoted to and adjustably connected with the beam; and it 10 has for its object to provide an improved construction, arrangement, and combination of parts whereby the said adjustment may be effected in a convenient manner and by which the standard when adjusted may be 15 securely retained in position.

My invention further consists in the improved construction of the detailed parts of the plow and of a drag attachment for the same, which will be hereinafter fully 20 described, and particularly pointed out in the claims.

In the accompanying drawings, Figure 1 is a side view of a plow constructed in accordance with my invention. Fig. 2 is a 25 sectional view taken on the line $x-x$, Fig. 1. Fig. 3 is a sectional view taken on the line $y-y$ of Fig. 1. Fig. 4 is a sectional view taken on the line $z-z$ of Fig. 1. Fig. 5 is a rear elevation.

30 Corresponding parts in the several figures are indicated by like characters of reference.

1 designates the plow-beam, the rear end of which is curved approximately to a semi-circular shape. The foot end of the beam is 35 provided on opposite sides with recesses 2, in which are seated the rearwardly-extending clamping-plates 3, the forward ends of the upper edges of which abut against the shoulders 4 at the upper edges of the recesses 2. 40 The plates 3 are secured in position by means of a transverse pin 5.

Between the clamping-plates 3, near the rear ends thereof, is mounted the L-shaped drag 6, which consists of a steel bar of suitable dimensions bent at right angles and having its vertical arm inserted between the clamping-plates 3, where its upper forward end rests against a transverse pin or rivet 7, while its rear side has a bearing against a 45 clamping-bolt 8, which also extends transversely through the plates, near their lower rear corners, and which is provided with a

nut 9, which may be tightened so as to hold the drag securely in position at any desired point of vertical adjustment. The handles 55 10 10 are also secured to the clamping-plates, upon the outer sides of the latter, by means of transverse pins or bolts 11, which are arranged diagonally with relation to the pins 7 and bolt 9, thus providing additional supports for the vertical member or shank of 60 the drag.

The standard proper, which is designated 12, is composed of two plates or bars 13 13, which are of an elongated-S shape and which 65 are placed on opposite sides of the beam with which they are connected, near the point or foot end thereof, by means of a transverse pin or bolt 14, which extends through the point of the beam and also through the 70 clamping-plates located on the sides thereof. The point of attachment of the bars composing the standard 12 may be varied at will, but I prefer that it should be distant about one-third of their length from the points or 75 lower ends of said bars. The latter are spaced at their lower ends by an interposed block 16, through which a connecting bolt or rivet 17 extends.

The parts thus far described are preferably 80 constructed of steel.

I shall now proceed to describe the adjusting mechanism, which is mainly to be constructed of cast-iron.

18 designates a plate or bracket secured to 85 the curved part of the beam and extending rearwardly from the same. The said bracket is provided on one side thereof with an annular rim or collar 19, surrounding a perforation 20, which is to receive a pin or bolt 21, 90 by means of which the said bracket is connected with the end of one arm of a bell-crank lever 22, which said arm is provided with an opening 23, whereby it has a pivotal movement upon the flange 19. The other 95 upwardly-projecting arm of the bell-crank lever is formed at its upper edge with a toothed segment 24, and at its fulcrum it has an annular rim or flange 25 surrounding a perforation 26 to receive a pin or bolt 27, 100 whereby it is connected with the operating-lever 28, which latter has a perforation whereby it is mounted upon the flange 25, on which it has a pivotal movement. The lower

end of the lever 28 extends between the plates 13 of the standard 12 at the upper end of the latter, and it has pivotal connection with said plates by means of a pin or bolt 29.

- 5 The operating-lever is provided on one side thereof with lateral projections or brackets 30, which are perforated for the passage of an operating-rod 31, which is provided at its lower end with a tooth 32, engaging the 10 toothed segment of the bell-crank lever 22. The upper end of the rod 31 is bent to form a handle 33, which may be conveniently grasped by the operator. The operating-rod 31 is also provided near its lower end with a 15 shoulder 34 to receive the impact of a spring 35, which is coiled upon the said rod and the upper end of which has a bearing against the under side of the upper projection 30.

The operation of this invention will be 20 readily understood from the foregoing description, taken in connection with the accompanying drawings. By means of the operating-lever when the tooth 32 is disengaged from the toothed segment 24 the standard 25 may be adjusted to any desired tilt, thus causing the plow, the blade of which is attached in the usual manner to said standard, to run deep or shallow, as may be desired. The standard will be locked in its operative position 30 by the tooth 32 engaging the toothed segment 24. The drag also may be very readily adjusted when the bolt 9 is loosened so as to release the grip of the clamping-plates upon the shank of said drag.

35 The component parts of my improved plow may be manufactured of any desired material and of any desired dimensions, and I reserve the right to make any changes as to the detailed construction and arrangement of the 40 parts which may be resorted to without departing from the spirit of my invention.

Having thus fully described my invention, what I claim as new, and desire to secure by Letters Patent, is—

- 45 1. In a plow the combination of a beam provided at the foot thereof with recesses having shoulders at their upper edges, rearward-extending plates seated in said recesses and secured by transverse fastening means, a drag 50 having a shank disposed between said plates, a pin connecting the latter and forming a support for the upper front edge of said shank and a clamping-bolt connecting said plates at a point diagonally opposite to said connecting-pin, substantially as set forth.

55 2. The combination of a plow-beam, clamping-plates extending rearwardly from the point thereof, a drag having a shank disposed

between said plates, a pin connecting the latter and forming a support for the upper front 60 edge of said shank, bolts supporting the handles of the plow and extending transversely through the clamping-plates and forming points of support for the shank of the drag, and a bolt extending transversely through 65 said clamping-plates at the heel ends thereof and provided with a clamping-nut, said bolt forming a point of support for the rear edge of the shank of the drag, substantially as set forth.

70 3. The combination of a plow-beam, having recesses on opposite sides of the point thereof, the clamping-plates secured in said recesses, the standard-blades having pivotal connection with the plow-beam by means of a pin 75 passing through the clamping-plates, a spacing-block at the lower ends of said standard-plates, a bracket extending rearwardly from the beam, a bell-crank lever having one end pivotally connected with said bracket and 80 having a toothed segment at its other end, an operating-lever fulcrumed at the angle of the bell-crank lever and having its lower end extended between the upper ends of the standard-plates and pivotally connected therewith, 85 and means carried by the operating-lever for engaging the toothed segment of the bell-crank lever thereby retaining the parts at any point to which they may be adjusted, substantially as set forth.

90 4. The combination of a beam, a bifurcated standard having pivotal connection therewith, a bracket secured to the beam, extending rearwardly and having a perforation reinforced by a surrounding flange, a bell-crank 95 lever, one of the arms of which has pivotal engagement with said reinforcing-flange and the other arm of which terminates in a toothed segment, said bell-crank lever being provided at the angle thereof with a transverse perforation reinforced by a surrounding flange, an operating-lever mounted pivotally upon said flange, a pivotal connection between the lower end of the operating-lever and the upper end of the bifurcated standard, connecting means 100 at the several pivotal points, and means carried by the operating-lever for engaging the toothed segment of the bell-crank lever, substantially as set forth.

105 In testimony that I claim the foregoing as my own I have hereto affixed my signature in the presence of two witnesses.

BEVERLY GRAY REEVES.
